UNITED STATES PATENT OFFICE.

ALONZO L. EDWARDS, OF WHEELING, WEST VIRGINIA, ASSIGNOR TO WHEELING STAMPING COMPANY, OF WHEELING, WEST VIRGINIA, A CORPORATION OF WEST VIRGINIA.

DESIGN FOR A LANTERN.

44,523.

Specification for Design.

Patented Aug. 19, 1913.

Application filed April 15, 1913. Serial No. 761,348. Term of patent 14 years.

To all whom it may concern:

Be it known that I, ALONZO L. EDWARDS, a citizen of the United States, residing at Wheeling, Ohio county, West Virginia, have invented a new, original, and ornamental Design for Lanterns, of which the following is a specification, reference being had to the accompanying drawing, forming part thereof.

The figure is a perspective view of a lantern, showing my new design.

I claim:

The ornamental design for a lantern, as shown.

In testimony whereof, I have hereunto set my hand.

ALONZO L. EDWARDS.

Witnesses:

DORN MORRIS,
M. B. BAILEY.
